Patented Mar. 1, 1927.

UNITED STATES PATENT OFFICE.

RUDOLPH A. KUEVER, OF IOWA CITY, IOWA, ASSIGNOR TO PEPSODENT COMPANY, OF CHICAGO, ILLINOIS, A CORPORATION OF ILLINOIS.

CLEANSING AND POLISHING AGENT.

No Drawing.

Application filed December 12, 1924. Serial No. 755,369.

My invention relates more particularly to an improved dentifrice to be compounded in the form of either a paste or a dry powder, but its utility is not restricted to such use as the substances described and claimed possess advantages for other uses as cleansing and polishing agents. A dentifrice, however, must possess certain properties which are not necessary in polishing and cleansing agents for other uses.

It has been discovered that dentifrices having an acid reaction possess advantages over substances or mixtures of substances having a neutral or alkaline reaction, the generally accepted explanation of this fact being that the acidity of such a dentifrice stimulates the flow of the saliva and that it also increases the alkalinity of the saliva. In addition to having an acid reaction it is also essential that a dentifrice consist of or contain a substance which in the powdered form will have the necessary mechanical action when rubbed or brushed upon the teeth to effect the cleansing and polishing of the tooth surfaces, and the substance used for this purpose should be of such hardness as to perform the cleansing and polishing functions without injurious or, if possible, without any, abrasion of the tooth substance, and it should be of such a degree of solubility that it will resist solution until after the cleansing and polishing is effected but will enter into solution in the fluids of the mouth shortly thereafter.

The necessity for the degree of solubility above described resides in the fact that one of the principal sources of trouble arising from the use of dentifrices consists in the lodgment under the gum margins of particles of the polishing agent. This lodgment of the polishing agent under the gum margins gives rise to irritation and inflammation and eventually exposes the gums to infection. This disadvantage may be eliminated by employing a polishing and cleansing agent that is sufficiently soluble to enter into solution in the mouth fluids within a comparatively short time after the cleansing and polishing of the teeth have been effected. Agents possessing the degree of solubility described quickly dissolve after lodgment under the gum margins whereby the cause

of irritation is eliminated before any harmful effect is produced.

I have found that the degree of solubility of an efficient polishing and cleansing agent for the purpose of a dentifrice is less than 1 in 200, and that satisfactory results in respect to solubility are attained by the use of an agent having a solubility in the neighborhood of 1 in 1200. This degree of solubility insures that the polishing and cleansing agent will resist solution during the cleansing and polishing operation but will enter into solution after lodgment under the gums before any injurious effect has been produced.

The degree of hardness of a cleansing and polishing agent used upon the teeth should be such as to avoid any abrasion whatsoever of the tooth substance, but should at the same time be of such hardness as to effect the necessary cleansing and polishing.

In compounding a dentifrice there is no difficulty in imparting to it the necessary acid reaction by the use of suitable fruit acids or other acid substances provided the polishing and cleansing agent and other ingredients, if any, do not by their alkalinity neutralize the acid or acid substance.

I have discovered that certain salts consisting of inorganic bases combined with hydroxy organic acids possess the requisite combination of properties, being neutral in reaction and possessing the proper degree of hardness and solubility. Calcium carbonate in the form of ordinary chalk has heretofore been used to some extent as a dentifrice but neither in hardness nor in solubility does it conform to the requirements above described. I have found, however, that the substitution for carbonic acid of certain of the hydroxy organic acids produces with calcium a neutral salt having the degrees of hardness and solubility above described, and that substantially similar compounds are formed by the combination of these hydroxy organic acids with other elements of the alkaline earth group. Among the salts which I have found especially adapted for use as a dentifrice is calcium citrate. This substance is neutral in reaction, is of the requisite solubility and has a hardness of about 1 upon the standard scale of hardness. For

efficient cleansing and polishing the degree of hardness should not be materially less than 1 and should be less than 3.5, the hardness of the tooth structure ranging ordinarily from 3.5 to 7.

For use as a dentifrice it is of course necessary that the polishing and cleansing agent be innocuous in addition to possessing the other properties above described. I have found that these properties are fulfilled by calcium citrate and also by calcium tartrate and strontium tartrate, and that certain other alkaline earth salts of hydroxy organic acids, such as barium citrate, possess the requisite properties for polishing and cleansing but are unavailable for use in dentifrices by reason of other properties.

The freedom from abrasive effect upon the tooth substance of the salts referred to above of hydroxy organic acids appears to be related not only to their degree of hardness but also to some other property, as I have found that calcium citrate produces no abrasive action upon the teeth while other compounds composed entirely of inorganic substances and of substantially the same degree of hardness do abrade the tooth structure. I have subjected gold crowns and tooth structure to the prolonged polishing action of calcium citrate without producing any abrasion whatsoever and resulting only in the production of a high polish while similar use of polishing agents of substantially equal hardness and composed entirely of inorganic substances has resulted in destructive abrasion. This indicates that the salts which I employ possess properties not found in purely inorganic substances or in salts of the character of calcium carbonate, and that these properties are especially advantageous

in a dentifrice and also useful for other purposes.

Following is an illustrative formula of a dentifrice embodying my invention:

Ingredients.	Parts.
Calcium citrate	100
Citric acid	3
Gums (used as a binder)	3
Glycerine	40
Water	40
Flavoring	50

The above formula is for the preparation of a dentifrice paste. As above stated, calcium citrate is neutral in reaction. The free citric acid imparts the necessary acidity. Other fruit acids or suitable substances having an acid reaction may be used in place of citric acid. The gums are used as a binder and serve to preserve the homogeneous consistency of the paste.

While in the following claims I refer to my invention as a dentifrice I contemplate its use for other purposes as coming within the scope of the invention.

I claim as my invention:

1. A dentifrice comprising a cleansing and polishing agent consisting of calcium citrate.
2. A dentifrice comprising calcium citrate and a substance having an acid reaction.
3. A dentifrice comprising calcium citrate and a binder mixed to form a paste.
4. A dentifrice comprising calcium citrate and glycerine.
5. A dentifrice comprising calcium citrate, a binder and glycerine mixed to form a paste.

Signed at Iowa City, Iowa, this 9th day of Dec., 1924.

RUDOLPH A. KUEVER.
